UNITED STATES PATENT OFFICE.

WILLIAM CAVANAGH, OF PROVIDENCE, RHODE ISLAND.

LOOM.

SPECIFICATION forming part of Letters Patent No. 550,405, dated November 26, 1895.

Application filed June 26, 1895. Serial No. 554,071. (No model.)

To all whom it may concern:

Be it known that I, WILLIAM CAVANAGH, of the city of Providence, in the county of Providence and State of Rhode Island, have 5 invented certain new and useful Improvements in Open-Shed Fancy Looms; and I hereby declare that the following is a full, clear, and exact description of the same, reference being had to the accompanying drawings, forming part of this specification.

This invention has reference to an improvement in open-shed fancy-looms; and it consists in the peculiar and novel construction of mechanism for stopping the loom and operating the evener-slide, as will be more fully 15 set forth hereinafter.

In open-shed fancy-loom when a warp-thread breaks or ends require to be tied in the harnesses require to be evened, so as to 20 lay the warp side by side and enable the operative to piece up the warp or tie in the ends required. In such looms as they are at present constructed this requires much care and time.

25 In such looms as heretofore constructed the evener-slide had to be drawn out by hand after the lay was brought into the proper position, and then the harnesses had to be brought together by hand. After the ends were tied in 30 the parts had to be returned to their original positions by hand before the loom was ready to start.

The object of the present invention is to 35 perform all these operations automatically through setting in motion a simple apparatus connected with a cord extending practically around the loom by pulling the cord.

To enable others versed in the art to more 40 clearly understand and practice my invention, I will describe the same more fully fully in connection with the parts of an open-shed fancy loom with which the mechanism co-operates.

Figure 1 is a skeleton view of parts of an 45 open-shed fancy-loom, showing the improvement connected with co-operating parts. Fig. 2 is a perspective view of the levers connecting with the crank-shaft of the lay of the loom. Fig. 3 is a side view of a modified form 50 of the device.

Similar letters of reference designate corresponding parts throughout.

In the drawings, A indicates the lay of an

open-shed fancy loom; B, the connecting-rod connecting the lay with the crank of the shaft 55 C. The shipper or stop-lever D is secured to the shipper or stop-shaft E, and supported in the raised frame F is the evener-slide T.

The parts so far described are the essential parts of every open-shed fancy-loom. As my 60 improvement concerns only these parts, the other parts of the loom are omitted, so as to avoid confusion and to point out the improvement more clearly.

The preferred means for carrying out my invention consists in the lever g, loosely mounted on the shipper-shaft E close to the shipper-lever D. The upper projection of the lever g is provided with the pin g', bearing on the shipper-lever D. To the lower end of the 70 lever g is pivotally connected the arm h, the other end of this arm h being provided with the shoulder h'. The arm h is supported in the slotted bracket i, preferably secured to the end frame of the loom, as is shown in 75 Fig. 1. The bracket k is secured to the arm h, and near this is the eye l, to which the cord m is fastened. This cord m is carried over rolls or other guides along the end around part or the whole of the loom, the end of the 80 cord being secured to any fixed place, preferably a part of the loom, and at such a height that it does not interfere with the work of the operative or the loom and is within easy reach 85 of the operative.

On the crank-shaft C the wiper-cam n is secured so as to rotate with the crank-shaft. The shoulder n' of the wiper-cam n is designed to engage with the shoulder h' on the end of the arm h when this arm is raised. Close to the 90 cam n and also secured to the crank-shaft C is the cam o, provided with the shoulders o' and o''. The evener-slide T is provided with the slotted head p. The lever q, pivoted to the bracket r, secured to the frame F, is provided 95 at its upper end with a pin s, which extends through the slot in the head p on the evener-slide T. To the lower part of the lever Q is connected pivotally the arm u, which extends through the slot in the bracket i, and is provided at its free end with two shoulders u' and u''. To the arm u, on its under side, is secured the bracket v.

In the normal condition, when the loom is running, the arm h rests in the slotted bracket 100 i and supports, by means of the brackets k 105

and *v*, the arm *u* in the position shown in Fig. 2. The cams *n* and *o* revolve without interfering with the arms *h* and *u*. When, now, to tie in ends or piece the warp, the loom requires to be stopped and the warp evened, instead of performing the operations required in an open-shed fancy loom as herein first described, the operative pulls on the cord *m* and raises the arm *h*, the shoulder *n'* of the cam *n* 5 comes in contact with the shoulder *h'* and pushes the arm *h* and the lower end of the lever *g* forward, and the pin *g'* operates the shipper-lever *D* to stop the loom. In the movement of the arm *h* the bracket *k* passes beyond the 10 bracket *v*, the arm *u* descends, the shoulder *o'* of the cam *o* encounters the shoulder *u'* of the arm *u* and draws this arm rearward and with it the lower end of the lever *q*, the upper 15 end of which draws the evener-slide sidewise and, as it is supported on pins entering diagonal slots, it raises the evener-slide and operates the harnesses to even the warp in the usual manner and by the old well-known 20 means.

25 After the piecing is completed the lay *A* is pushed back, thus partly rotating the crank-shaft *C* and cam *o*, the shoulder *o''* comes in contact with the shoulder *u''* and pushes the arm *u*, with the lower end of the lever *q*, forward and the evener-slide *T* inward and downward into the original position. The shipper-lever *D* is now drawn forward to start the 30 loom, and, by coming in contact with the pin *g'*, the lever *g* pushes the arm *h* backward, the bracket *k*, coming in contact with the bracket *v*, lifts it and the arm *u* and supports the same in the position shown in Fig. 2. By this arrangement the pull on the cord *m* sets the 35 mechanism in operation to stop the loom and even the harnesses, and a push on the lay puts the loom in condition to be started by the shipper-lever.

40 While the arrangements of the various parts of my improved mechanism have been found in practice to accomplish the desired result, I do not wish to confine myself to the exact construction shown.

45 In the modified form shown in Fig. 3 the arm *h* is connected by the lever *4* with the arm *u*³, which is pivoted to the lever *q*. The lever *4* is pivoted in the slot of the bracket *i'* and only the cam *n* is secured to the crank-shaft *C*. In this modified form the cam *n* 50 will have to be accurately adjusted, so that the shipper motion to stop the loom and the movement of the evener-slide will correspond with the movements of the harness-operating mechanism.

55 The parts of my improved mechanism used for operating the shipper-lever may be used on other kinds of looms.

Having thus described my invention, I claim as new and desire to secure by Letters Patent—

1. In an open-shed fancy loom, the combination with the shipper-lever, the lay-crank-shaft, and the evener-slide, of a wiper secured to the lay-crank-shaft, an arm suspended near one end below the wiper and connected at the other end with a lever loosely mounted on the shipper-shaft and said lever constructed to engage with the shipper-lever, a cord connected with and adapted to raise the end of the arm suspended below the wiper, a pivoted lever one end of which is connected with the evener-slide, an arm pivotally connected with the opposite end of the pivoted lever, and connections between the two arms constructed to support the upper arm; the whole adapted to operate the shipper-lever and the evener-slide, as described. 65

2. In an open-shed fancy loom, the combination with the evener-slide, of a lever, pivotally supported on the frame, connected at its upper end with the evener-slide, an arm 70 pivotally connected with the lower part of the lever, a wiper-cam secured to the lay-crank-shaft, a hand-operated device for engaging the pivoted arm and the wiper-cam, and mechanism, substantially as described, between 75 the pivoted arm and the wiper-cam, adapted to operate the evener-slide, as described. 80

3. The combination with the lay crank-shaft and the shipper-lever of a loom, of the lever *g* connected with the shipper-lever, the 85 arm *h* pivotally connected to the lever *g* at one end, the wiper-cam *n* secured to the lay-crank-shaft, and the cord *m*, secured at one 90 end to the arm *h*, extending over supports and having the other end secured to the loom-frame, constructed to raise the end of the arm *h* into engagement with the wiper-cam to stop 95 the loom, as described. 100

4. In an open-shed fancy loom, the combination with the shipper-lever *D*, the lever *g* 105 mounted on the shipper-shaft the lay-crank-shaft *C* and the evener-slide *T*, of the wiper-cam *n* secured to the lay-crank-shaft, the arm *h* one end of which is supported by the cord *m* and the other connected with the lever *g*, 110 the cam *o* having shoulders *o'* *o''* also connected with the lay-crank-shaft, the arm *u* 115 provided with the shoulders *u'*, *u''* adapted to engage with the cam shoulders *o'* and *o''*, connections between the arm *u* and the evener-slide *T*, and connections between the arm *h* 120 and the shipper-lever *D*, and the cord *m*; the whole constructed to automatically operate the evener-slide and shipper-lever when the cord is pulled so as to raise the arm *h*, as described.

In witness whereof I have hereunto set my hand.

WILLIAM CAVANAGH.
